JOHN P. NORDELL, OF NEW YORK, N. Y.

TOWING MINES.

1,341,578.

Specification of Letters Patent.

Patented May 25, 1920.

Application filed April 21, 1917. Serial No. 163,672.

To all whom it may concern:

Be it known that I, JOHN P. NORDELL, a citizen of United States of America, residing at New York city, in the county of 5 Bronx and State of New York, have invented new and useful Improvements in Towing Mines, of which the following is a specification.

This invention is a torpedo or mine defense wherein the submerged mines or torpedoes are towed and permitted to spread out and away from the towing vessel so that they will cover a large area, and by the peculiar formation of the float to which the 10 mine or torpedo is attached, each float will move forward in a direction parallel to that of the towing vessel at a slight angle thereto to permit a pulling force to be exerted on the several floats.

20 The usual manner of towing mines or torpedoes causes them to follow substantially in the path of the towing vessel and as it is desired that the mines or torpedoes be kept spaced apart a more or less rigid element must be employed.

In this invention, the formation of the float accomplishes this purpose, and this float, when acted upon by a pull that is exerted at a slight angle to its longitudinal 30 axis, is caused to move in a forward direction, and the several floats will arrange themselves in a wide-mouthed V-shaped formation according to the amount of pull on them and the speed of the towing vessel.

35 The floats in this invention are so shaped that they will present a surface that will readily pass through the water with a tendency to move at an angle against the pulling force, and at the same time the speed 40 at which they are drawn through the water by the vessel will cause them to maintain a position near the surface by means of a peculiarly shaped plane or horizontal rudder carried on the upper edge of each of the 45 planes near its forward end.

Each of the floats has depending therefrom a mine or torpedo, the depth of immersion being regulated by its weight, and in order that the floats may readily pass 50 through the water with little resistance they are provided with cone- or ogival-shaped ends, and in order that they may be moved in a forward direction due to the pulling force communicated to the float, they are 55 provided with a rudder. This rudder may be straight or curved according to the par-

ticular direction the mine or torpedo is required to move relatively to the float and to the water.

Broadly stated, the invention comprises a series of floats so shaped that they will present a relatively small surface in passing through the water and which have upon their upper edge a plane so shaped that when the float is drawn through the water it 60 operates to lift the float, beginning at its forward end, one edge and one side surface of the edge of the floats presenting a curved outline, means disposed upon the two side surfaces and the lower edge to permit of the 65 attaching of flexible means, and means disposed upon the lower edge connecting directly with an immersed torpedo or mine of a cylindrical outline having cone- or ogival-shaped ends and a rudder disposed adjacent one of the ends, the attaching means 70 disposed upon the side surfaces of the float being employed for connecting several floats together and also to afford means for connecting the floats for towing purposes. 75

One practical form of construction will be described and illustrated in the accompanying drawings, in which:—

Figure 1 is a diagrammatic view;

Fig. 2 is a side elevation of a float and 85 its depending mine or torpedo;

Fig. 3 is a series of sectional views of one of the floats;

Fig. 4 is a bottom plan view of a float; and

Fig. 5 is a top plan view of a float. 90

In the preferred embodiment to be hereinafter described, the towing vessel indicated at 10 is of a submarine or submersible type. Extending from this vessel 10 is a 95 towing cable 11, which is secured to a series of floats so that they may be towed upon the port side, and at 12 is indicated another towing cable which is secured to another series of floats so that they may be towed 100 upon the starboard side.

The floats may be formed of any suitable material and may be made solidly of wood or may be made of metal which provides an air-tight compartment to produce buoyancy 105 in the float. Each of the floats is provided with a body portion A having an upper edge that comprises a curved portion indicated at 13 that connects with a straight portion 14. This straight portion 14 communicates 110 with a straight or vertical end indicated at 15.

As shown in Fig. 3, the float is of varying vertical heights, and these varying heights produce a curved upper edge that includes the straight portion. The lower edge 16 is 5 provided with attaching means indicated at 17 and 18. These means may be of any suitable construction. As shown in Fig. 2 the lower edge extends in a direction substantially at right angles to the rear end 15 and 10 to the front end 19.

The top edge is provided with a notch having the horizontal portion 20 and the vertical wall 21. The vertical wall 21 is angularly connected with the curved top edge 15 13. This notch by its shape forms a bearing and shoulder for a transversely disposed rudder or guiding element, the top surface of which, indicated at 22, forms a continuation of the curved top edge indicated at 13. 20 As shown, this surface 22 inclines upwardly a little toward its front edge, indicated at 23.

As shown in Fig. 2, the rudder or guiding element is provided with a curved face indicated at 24 that extends transversely of the 25 float and of the front end 19. The rudder is so positioned and secured to the float that this transverse surface 24 may be angularly disposed with regard to the front edge 19 of the float.

30 The rudder, as shown in the top plan view, Fig. 5, has four sides. These sides are indicated by the numerals 25, 26, 27 and 23. As shown in Fig. 2 the side 27 extends downwardly from its point of juncture with the 35 front edge 23 and joins the rear edge 26.

The point of juncture of the rear edge 26 with the side 27 is substantially in a plane which conforms to the lower surface of the rudder where it rests upon the horizontal 40 portion 20 of the notch formed in the body A of the float. As is also shown in Fig. 2, the top surface indicated at 22 of this rudder is provided with a ridge portion indicated at 29. The surface 22 curves away from the 45 ridge portion 29 to connect with each of the sides 25 and 27. The point of juncture produces a very thin presenting edge as does the front edge 23 in coöperation with the under surface 24 of the surface 22. The under surface of this rudder or guiding element, indicated at B, is curved from front to rear as 50 well as being curved from the side 27 to the point of attachment of the rudder at the point indicated at 20 of the notch formed in 55 the float.

The other side of this rudder or guiding element is similarly formed so that the two surfaces presented to the water in passing through operate as planes tending to lift the 60 forward end of the float upward. The upper surface 22 by reason of its curved outline permits the front edge 28 to cut the water so that the water will flow over the rudder, or guiding element, in a stream line 65 manner without producing eddies or swirls

thereon to increase the friction as the float is moved forward in the water. This element by reason of the several curved surfaces and its transverse position on the float serves to ride the float upward to the surface and also acts to maintain the equilibrium of the float. 70

In Figs. 4 and 5 the particular longitudinal outline of the float is more clearly seen. Fig. 4 is a bottom plan view, and shows that 75 the float is provided with a flat surface or side indicated at 30, which extends between the front end 19 and the rear end 15. The other side of the float is of varying thickness, the curved portion of which being indicated at 31 and continuing rearwardly to a flat surface indicated at 32, which flat surface connects with the rear end 15. 80

As shown in Fig. 4, the curved surface 31 connects with the front end 19 forming 85 an acute angle therewith, which angle extends throughout the length of the float. This angular end serves to more readily permit of the float passing through the water in a longitudinal direction. By providing this curved side 31 in conjunction with the flat side 30, the float when pulled through the water tends to move in a direction at substantially right angles to the force acting upon it. The increase in speed 90 of the towing vessel and therefore in the amount of pull exerted upon the tow line tends to cause the floats to move out and away from the towing vessel. The floats will move outwardly due to these curved 95 surfaces until they travel in a direction parallel to the direction in which the towing vessel moves. The floats will then arrange themselves in a wide-mouthed V-shaped formation, or in other words the 100 tow line and the floats will project from the towing vessel in very nearly a right angular direction to the longitudinal axis of the towing vessel. 105

Disposed upon each of the surfaces 30 110 and 31 are attaching means indicated at 33 and 34. These attaching means are for the purpose of connecting a cable or other flexible element which serves to maintain the floats and their torpedoes in a spaced relation when being drawn through the water, and also serve upon one of them as a means 115 for attaching a tow line. As shown, these attaching means operate to pull each of the floats through the water in a sidewise 120 manner, that is the pull is so directed that a large surface of the plane offers resistance. 125

The cables used for connecting the several floats together are indicated at 35 and 36. Secured to the attaching means 17 and 18 carried upon the lower edge 16 of the float are flexible cables indicated at 37 and 38. These cables 37 and 38 are secured to the attaching means indicated at 39 and 130

40 carried by the torpedo or mine indicated at D. The torpedo or mine D is provided with cone- or ogival-shaped heads or ends, indicated at 41 and 42. The body 5 or cylindrical portion is indicated at 43.

Secured at the rear end in any convenient or usual manner is a rudder 28, which serves the purpose of directing the torpedo or mine D in a more or less straight direction 10 in accordance with the movement of the float through the water. The length of the flexible cables 37 and 38, which serve as depending means for the torpedo or mine D will preferably be such that 15 the torpedo or mine will be submerged to the proper depth.

The cylindrical portion 43 of the torpedo or mine D may serve as a container for an explosive and the end or head 41, may 20 also contain a suitable contact device or fulminate for the purpose of producing the combustion of the explosive.

What is claimed as new is:—

1. A torpedo and mine defense comprising a towing vessel, towing cables extending laterally therefrom, floats connected with the cables and each comprising a body portion with one vertical flat side and having its opposite substantially vertical side 25 deflected outwardly with reference to the main axis of the float and rearwardly of its nose portion, for maintaining the float in the course defined by the towing vessel, when the cables are taut, and explosive devices supported from the floats.

2. In a device of the class described, a float for supporting a torpedo and comprising a body portion, one vertical side of which is substantially parallel to the longitudinal axis of the float and is in an approximately vertical plane when the float 40 is in normal position, and the opposite side of which presents a curved surface for a portion of its length, and guiding means carried by the upper portion of the float 45 and projecting laterally and upwardly therefrom, the said guiding means being at approximately the water line when the float is submerged and carries a torpedo.

3. In a device of the class described, a 50 float adapted to support a torpedo, said float being higher toward one end than at the other end, an upwardly laterally and longitudinally extending member projecting from the forward end of the float at 55 approximately the water line, said float having a top, bottom, and sides, one side portion being deflected outwardly along a curved line to form a guiding member.

4. A torpedo and a float from which said 60 torpedo is suspended, the float comprising a body portion having one vertical flat side, parallel with the longitudinal axis of the float, and an oppositely located side deflected outwardly at a point forward of its 65 central portion, the float being of increased width at the deflected portion.

In testimony whereof I affix my signature.

JOHN P. NORDELL.
